DRAIN BOARD STRUCTURE

Eugene E. Brey, Pittsburgh, Pa., assignor to Tracy
Manufacturing Company, a corporation of
Pennsylvania

Application August 2, 1934, Serial No. 738,087

15 Claims. (Cl. 4—187)

This invention relates to a sink structure for installation in kitchens, pantries, lavatories, and generally similar localities.

A primary, and general, object of my invention is to provide a sink structure in which the drain board, and splash board, if one be included, are made of composite material comprising a rigid base material such as metal, and a covering of suitable non-metallic material such as 5 linoleum, rubber, cork composition, fiber, micarta, or the like, with all edges and joints firmly and neatly bound.

A specific object of my invention is to provide at the region in which the sink basin is attached to the drain board, or table portion, of the sink structure a compact and relatively heavy binding which is arranged to embrace and hold to each other at their edges the metallic base and non-metallic covering of the drain board or 10 table, and which is arranged cooperatively with clamps to engage and seal the edge of the basin.

Another object of the invention is to provide binding which bridges over the joint line between the non-metallic covering of the splash board and the non-metallic covering of the drain board, or table, of the sink, and which firmly interengages these coverings.

Another object of the invention is to provide simple but efficient means for firmly engaging and protecting the edge of the drain board, or 15 table, of the sink structure.

A still further object of the invention is to provide a sink structure having binding for the locations and purposes indicated which is attractive in appearance, contributing in detail and in general effect to the production of a sink of 20 particularly pleasing appearance.

In the accompanying drawings Fig. I is a top plan view of a sink embodying my improved 25 structural features.

Fig. II is a bottom plan view of the sink, showing the attachment of the sink basin to the drain board, or table portion, of the sink.

Fig. III is a cross-sectional view on an enlarged scale, taken on the plane III—III of Fig. II, showing in detail the structure for attaching the sink basin, with an edge binding, to the drain board, or table portion, of the sink, and showing the means for binding the joint between the 30 covering elements of the splash board and the drain board, or table portion, of the sink.

Figs. IIIa and IIIb are fragmentary cross-sectional views, on the scale of Fig. III, illustrating modifications in means for sealing the joint between the sink basin and the edging, or bind-

ing, element at the edge of the drain board surrounding the basin.

Fig. IIIc is a cross-sectional view illustrating on a materially enlarged scale the attachment of the basin to the drain board, and the common 5 means for sealing the joint between the basin and drain board and for binding the edge of the drain board surrounding the basin.

Fig. IV is a cross-sectional view taken on the line IV—IV of Fig. I, but on a larger scale than 10 that of Fig. I, illustrating particularly the binding at the outer edge of the drain board, or table portion, of the sink.

Figs. IVa and IVb are fragmentary cross-sectional views illustrating modifications in the edge 15 binding shown in Fig. IV.

In Figs. I and II of the drawings, reference numeral 1 designates the drain board of the sink, and reference numeral 2 designates the sink basin. In these figures of the drawings, reference 20 numeral 3 designates the splash board of the sink. The splash board 3 comprises a sheet metal base 3a, and a covering, or facing, 3b; and the drain board 1 comprises a sheet metal base 1a and a covering 1b.

It will be seen in Fig. III of the drawings that the metal base 3a of the splash board is provided with a flange 3c, which extends at right angles to, and parallel to, the plane of the base, and that it is fastened by rivets 3d with metallic 30 base 1a of the drain board, which in this region embraces a wooden stringer 4. A head strip 5 is mounted to crown the splash board. This head strip of suitable, light gauge metal has a 35 depending foot 5a fastened by rivets 6 to the portion of flange 3c of the base which parallels the body of the base, and a depending flange 5b, which depends over the upper edge of the non-metallic covering 3b, and seats in a rabbeted 40 region therein. This head strip, or crown, 5 is sprung into engagement, desirably by a slight difference in angularity between its foot 5a and flange 3c of the base. It may, however, be riveted 45 in position, as shown, because the covering 3b of the splash board is not subjected to wear or injury, and it is therefore unnecessary that it be readily replaceable. The means employed for binding the side edges of the splash board will be hereinafter described.

It will be noted that the non-metallic covering 50 3b on the splash board and the resilient covering 1b on the drain board are so mounted on their respective bases that they are not in actual contact with each other at their adjacent edges. The interval 55 60 between the edges of these cover-

ing elements is bridged by a strip 7, which is of substantial thickness, and which has longitudinal wings 7a and 7b, each disposed substantially perpendicular to the plane of the other.

The adjacent edges of both the splash board covering 3b and the drain board covering 1b are rabbeted, and the strip 7 lies in the rabbeting on both covering elements. At the rear of the intermediate region 1c of the strip 7, a bolt 8 is threaded to the strip. This bolt 8 lies in the interval 60 between the covering elements 1b and 3b, and projects through an opening 9 in the base 3a of the splash board. The bolt 8 also extends through a ferrule 10, against which bears a nut 11, on the rearward, also threaded, terminal of the bolt.

Reverse threads being provided at the opposite ends of bolt 8, strip 7 is drawn into firm engagement with the rabbeted seats of the covering elements by tightening action of nut 11, and the edges of the cover elements are clamped closely to the respective bases by the pressure of the strip.

Immediately cooperative means are provided for engaging the basin 2 to the drain board 3, to be suspended therefrom, to bind the edge of the drain board to surround the basin, and to seal the margin of the basin. As shown in Fig. III, such means comprise U-shaped brackets 12, each having one leg thereof adapted to bear against the under surface of the metal base 1a of the drain board, and its other leg adapted to bear against the under surface of a flange 2a, which extends angularly upward from the body of the basin. A bolt 13, having its head 13a countersunk in the base 1a of the drain board, extends through the bight of the U-bracket; and a nut 14, threaded to the lower end of the bolt, may be brought to bear against the outer surface of the bight.

An edging strip, or bar, 15 is arranged to bear against the upper surface of basin flange 2a, in opposition to one leg of the U-bracket 12. Edging bar 15, which extends completely around the junction between the basin and the drain board, has a smooth forward face presented toward the basin, and a recessed rearward face. The recess in the rearward face of the edging bar 15 is rectangular, or substantially rectangular, and receives the edge of the drain board.

The under face of the metal base 1a of the drain board lies squarely upon the upper face of lower leg 15a of the edging bar, and the upper leg 15b of the edging bar squarely overlies a rabbeted region 1c at the edge of the resilient covering element 1b of the drain board. The entire edge thickness of the drain board, as reduced by rabbeting, is thus received in, and embraced by, the rectangular recess of the edging bar provided by the body of the bar and its arms 15a and 15b.

It is to be understood that the resilient covering 1b of the drain board, as is also the covering 3b of the splash board, desirably is cemented to the metallic base upon which it lies. The edging is, however, important in order to prevent edge curling of the covering, which tends to take place even though the base and covering be cemented to each other all the way to their aligned edges. In order that the covering 1b of the drain board may to some slight extent creep, the edging bar 15 is so applied that a slight space 16 intervenes between the extreme edge of the drain board 1 and the base of the recess in the edging bar.

As noted above, one leg of each bracket 12 bears against the under face of the flange 2a of

basin 2, and the edging bar 15 lies upon the upper face of the flange. In order to seal the joint between the basin 2 and the edging bar, the edging bar is provided in its under face with a gutter 15c, which provides forward and rearward edges 5 for contact with the basin flange, and which provides a seat for packing. As shown in Figs. III and IV of the drawings, a tube 17 of rubber, or other yielding materials of which lead is a desirable example, lies in this recess, and is compressed 10 between the edging bar and the flange of the basin.

In the modification of Fig. IIIa, the flange 2a of the basin 2 is shown as straight, and the edges of the recess in the edging bar 15 are in alignment in the same horizontal plane, to suit the position of the flange. The packing 19 is shown as a coherent mass of rubber, or other suitable compressible material, rather than as tubular in form.

In the modification of Fig. IIIb, the form of the basin flange 2a is identical with that of Fig. IIIa. The edging bar 20 is, however, provided with two gutters, each of which receives a body 21 of packing.

The edge of the drain board may be formed in the various ways shown in Figs. IV, IVa, and IVb of the drawings. Referring particularly to Fig. IV, it will be noted that the outer edge of drain board covering 1b is rabbeted at 22 in a manner similar to that employed at the edge of the drain board surrounding the basin 2. In this seat 22 engages a leg 23a of an edging strip 23.

The edging strip 23 is of relatively light gauge resilient metal, and has a second leg 23b arranged to embrace a foot 24a, which extends perpendicular to a skirt 24 on the drain board base 1a, and which lies along the under face of a wooden stringer 25. In order that edging strip 23 may be locked resiliently in its edge binding 40 position, there should be a difference in angularity between the flange 24a of skirt 24 and foot 23b of edging strip 23. In the drawings this is shown as provided by a slight upward extension of foot 23b to form an acute angle with the vertical portion of the strip, whereas flange 24a is perpendicular to the body of skirt 24.

The leg 23a of edging strip 23 is bowed upwardly and a wooden strip 26, which is approximately hemispherical in cross-section, is fitted into the underlying concavity of leg 23a, and is lightly cemented thereto. It is sufficient that the strip 26 of wood, or other suitable material or composition, be lightly attached to edging strip 23a, as it is necessary merely that it be held there-to in mounting the strip on the edge of the drain board.

As mounted at the edge of the drain board, the flat under face of the filler strip 26 lies on the upper surface of the covering in the rabbeted edge region 22 of the covering. As the flat face of the filler strip 26 is pressed firmly into contact with the upper face of the covering in its rabbeted edge region, it serves to hold the edge of the covering 1b firmly to the marginal region of metal base 1a. It also serves to support the bowed region of the leg 23a of the edging strip, to prevent denting of this region by blows or pressure.

As shown in Fig. IV, the foot 23b of the edging strip is held against slippage from its engagement with flange 24a by a driving screw, which extends through the foot and flange and enters the stringer 25. This engagement is light, and does not force foot 23b into a position parallel with flange 24a. The resilient clinching ef- 75

fect of the edging strip is thus unaffected by this additional attachment.

The modification illustrated in Fig. IVa of the drawings shows a structure in which a stringer, such as the wooden stringer 25, is not used. In this modification there is an additional change in the resilient engagement of the edging strip with the drain board.

As shown, the skirt 27 depending from the edge of the metal base 1a of the board has a flange 27a which extends downwardly to a slight degree to form an obtuse angle with the body of the skirt. The edging strip 28 is identical in all respects to the edging strip of Fig. IV, save that the foot 28a extends perpendicularly to the body of the strip. The slight downward inclination of skirt flange 27a thus gives the difference in angularity for clinching the edging strip resiliently to the drain board.

20 A bolt 29, carrying a nut 39, engages foot 28a of the edging strip with flange 27a of the skirt 27. It will be noticed that bolt 29, also, does not force foot 28b into a position parallel to flange 27a, but that this engagement is sufficiently tight to 25 permit the resilient clinching of the edging strip to the drain board.

The structures shown in Figs. IV and IVa are those preferred in binding the outer edges of the drain board. It is to be understood that the features illustrated in both are interchangeable. That is, the manner of obtaining difference in angularity between the edging strip foot and the skirt flange may be used when a wooden stringer is employed, and conversely.

35 A simpler form of edge binding, which may be used at the outer edge of the drain board, and which is preferred as edging for the vertical side edges of the splash board, is shown in Fig. IVb of the drawings. The edging strip 31, shown in this figure of the drawings, has a foot 31b resiliently embracing flange 32a of a skirt 32, and attached positively thereto by a bolt 33. The upper leg 31a of the edging strip, however, extends perpendicularly to the body of the strip, 45 and lies directly and flatly against the upper surface of covering 1b in the region of a relatively shallow rabbeting therein.

As applied to the outer edges of the drain board 1, a single length of stripping desirably is 50 used along the front edge, and along each side edge. These strips may be mitered at the regions of their end abutment, and may be there welded or soldered to each other. The edging strips 31, as used along the side edges of the splash board, may also be cut terminally to the 55 contour of the crown strip 5 at the top of the splash board, and welded or soldered to it.

It should be understood that side boards may be added to the sink assembly to meet the back 60 board of the sink structure. If the splash board assembly of the structure is made to comprise side boards, as well as a back board, the junction lines between the drain board and the side boards, and the junction lines between the side boards and the back board, are bound interiorly of the structure by bridging strips similar to the bridging strip 7, which binds the junction line between the drain board and the back board.

To summarize my invention: a sink structure 70 comprising a splash board and drain board of sheet metal are both provided with layers of suitable covering material. A basin is mounted on the drain board, to lie below the level thereof. The edges of both the splash board covering and 75 the drain board covering are rabbeted along their

edges and metallic binding strips resiliently, or by external pressure, are mounted positively to clamp the coverings to the metallic bases of the splash board and drain board. The adjacent edges of the drain board and splash board are 5 not only held to their respective bases, but the joint line therebetween also is finished off by a binding strip common to both coverings.

The various forms of edge binding used, each form adapted to the location in which it is applied, cooperate in the assembly to produce a sink structure in which the covering elements of linoleum, or the like, are protected against wear, and are held positively against separation from the metallic base elements on which they are mounted. They cooperate in producing an assembly 15 of highly finished, and particularly pleasing, appearance.

The edging strip structure is made the subject-matter of a divisional application Serial No. 20 13,928, filed March 30, 1935.

The edging strips binding the outer edges of the drain board, and the edges of the splash board, are desirably, though not necessarily, made of stainless steel, or chrome plated metal. The 25 strips, or bars, used at the junction line between the splash board and drain board, and to bind the drain board edge surrounding the basin, desirably, but not necessarily, are formed by the extrusion of aluminum, or other suitable, extrudable, metal.

As used throughout the specification, and the appended claims, the word "sink" is used as a word of description, and not of limitation. It is to be understood that flat elements of tables, 33 shelves, and various other portable or installed pieces of furniture, may comprise similar composite material organized by cementing a resilient covering to a metallic base and by similarly applying metallic edging strips to bind the edges of 40 the composite material.

While it is highly desirable that the covering be in each composite plane element cemented to the metallic base, for purposes of manufacturing convenience, and as a safeguard against intermediate bulging of the cover away from the base, I do not intend to limit my invention to a structure in which the coverings are cemented over all or part of their area to the metallic bases on 45 which they lie.

I claim as my invention:

1. A sink comprising a table top and back board both of composite structure having each a sheet metal base and a covering of non-metallic material on the base, both the back board and the table top having metallic binding strips embracing the metallic base and the non-metallic covering of each along the outer edges thereof, the non-metallic coverings of the back board and table top being applied to their respective bases to 55 leave an interval between coverings extending along the junction line between the table top and the back board, the adjacent edges of the table top covering and back board covering being rabbeted, a relatively rigid strip seated in the 60 rabbeting of both the table top and the back board, and means for pressing said strip firmly and uniformly upon both covering elements.

2. A sink assembly comprising the combination of a drain board and splash board both of composite structure and having each a sheet metal base and a covering of non-metallic material on the base, both the splash-board and the drain board having metallic binding strips embracing the metallic base and the non-metallic covering of 65 70 75

each along the outer edges thereof, and an opening extending through the composite structure of the drain board, together with a basin lying below the drain board in the region of the opening therein, a binding strip or bar arranged to embrace the edge of said composite drain board surrounding the opening therein, and clamps having connection with the drain board and arranged to hold the edge of the basin against said binding strip or bar.

10. 3. A sink assembly in accordance with the combination of claim 2 in which the binding strip or bar has a gutter for the reception of packing facing toward the edge of said basin, and yielding packing material in said gutter and forming a seal between said packing strip and said basin.

15. 4. In a sink the combination of a drain board comprising a composite structure having a sheet metal base and a covering of non-metallic material thereon, an opening through said drain board, a binding strip or bar having in a side face thereof a recess arranged to embrace the edge of the composite drain board to prevent edge movement of the covering away from the metallic base, a basin lying below the plane of the drain board and having an upper edge arranged to contact said binding strip or bar, and clamps having connection with the drain board and arranged to hold the edge of the basin against said binding strip or bar.

20. 5. A sink constructed in accordance with the combination of claim 4 in which the binding strip or bar has a gutter for the reception of packing facing toward the edge of said basin, and yielding packing material in said gutter and forming a seal between said packing strip and said basin.

25. 6. In a sink or similar article of manufacture the combination of two plane elements joined at an angle to each other, each of said plane elements comprising a sheet metal base and a covering of non-metallic material on said base, the non-metallic covering of both structural elements being applied to their respective bases to leave an interval between coverings extending 30 along the junction line between the structural elements, the adjacent edges of the coverings on both elements being rabbeted, a strip of relatively rigid material seated in the rabbeting in the coverings of both the said structural elements, with 35 its longitudinal edges in contact with the shoulders formed by the rabbeting and with its outer surface providing a concave continuation of the outer surface of the coverings, and means for pressing said strip firmly upon the covering of 40 both elements in the rabbeted regions of said coverings.

45. 7. The combination of claim 6 in which both of said structural elements are provided along their edges with metallic binding arranged to preserve edge contact between the metallic bases and the non-metallic coverings of the said elements.

50. 8. The combination of claim 6 in which at least one of said plane structural elements has there- 55 in an intermediate opening at which a binding bar embraces the edge of the composite structure of the element surrounding the said opening and is clamped thereto.

55. 9. In a sink the combination of a drain board comprising a composite structure having a sheet metal base and a covering of non-metallic material thereon, an opening through said drain board, a binding strip or bar having in a side face thereof a recess arranged to embrace the 60 edge of the composite drain board at said open-

ing, a basin lying below the plane of the drain board and having a laterally extending flange arranged for contact of its upper face by the under face of said binding strip or bar, clamps having connection with the drain board and arranged to hold the flange of the basin against said binding strip or bar, a recess in the under face of said binding strip or bar providing in assembly a wholly enclosed space between the flange of the basin and the body of said binding strip or bar, and compressible packing material wholly housed within said recess and compressed by the compressive effect of the clamps holding said basin to said binding strip or bar.

10. 10. In a sink the combination of a drain board comprising a composite structure having a sheet metal base and a covering of non-metallic material thereon, an opening through said drain board, a binding strip or bar having in a side face thereof a recess arranged to embrace the edge of the composite drain board at said opening, a basin lying below the plane of the drain board and having a lateral extension arranged with its upper face in contact with the under face of the binding strip or bar, a plurality of bolts mounted in the metallic element of the drain board to extend therebeneath and with their uppermost extension lying beneath the non-metallic covering of the drain board, and clamping means of general U-shape engaged by said bolts and arranged to contact the under face of the drain board and the under face of the lateral extension of the basin to engage the basin to the binding strip or bar and to the drain board.

15. 11. In a sink the combination of a drain board comprising a composite structure having a sheet metal base and a covering of non-metallic material thereon, an opening through said drain board, the non-metallic covering material of the drain board being rabbeted along the edge of said opening, a binding strip or bar formed with laterally projecting legs defining a lateral recess, said binding strip or bar being so proportioned and arranged that the upper lateral leg of the bar lies upon the non-metallic covering of the drain board in the rabbeted zone thereof and the lower laterally extending leg of the binding strip or bar extends beneath the metallic base of the drain board, a basin lying below the plane of the drain board and having a lateral extension with its upper face arranged to contact the under face of said binding strip or bar, and clamps having connection with the drain board and arranged to hold the basin against said binding strip or bar.

20. 12. In a sink the combination of a drain board comprising a composite structure having a sheet metal base and a covering of non-metallic material thereon, an opening through said drain board, the non-metallic covering material of the drain board being rabbeted along the edge of said opening, a binding strip or bar formed with laterally projecting legs defining a lateral recess, said binding strip or bar being so proportioned and arranged that the upper lateral leg of the bar lies upon the non-metallic covering of the drain board in the rabbeted zone thereof and the lower laterally extending leg of the binding strip or bar extends beneath the metallic base of the drain board, a basin lying below the plane of the drain board and having a lateral extension with its upper face arranged to contact the under face of said binding strip or bar, a plurality of bolts mounted in the metallic element of the drain board to extend therebeneath and with their uppermost extension lying beneath the non-metallic covering of the drain board, and clamps having connection with the drain board and arranged to hold the basin against said binding strip or bar.

their uppermost extension lying beneath the non-metallic covering of the drain board, and clamping means engaged by said bolts and arranged to contact the under face of the drain board and 5 the under face of the lateral extension of the basin to engage the basin to the binding strip or bar and to the drain board.

13. In a sink or similar article of manufacture the combination of two plane elements joined at 10 an angle to each other, each of said plane elements comprising a sheet metal base and a covering of yielding non-metallic material of substantial thickness on said base, the non-metallic covering of both structural elements being applied to their respective bases to leave an interval 15 between the coverings extending along the junction line between the structural elements, the adjacent edges of the coverings on both elements being rabbeted, a strip of relatively rigid material comprising two wings extending angularly to 20 each other and inset respectively in the rabbeting of the two said coverings to have both face and edge contact with the coverings, said strip being engaged in its said position firmly to hold in position 25 the edges of said non-metallic coverings.

14. In sink construction the combination of a drain board and splash board, each of said elements comprising a base of sheet metal and a covering of compressible non-metallic material 30 thereon, metallic edge binding around the free edges of both the drain board and the splash board providing edge engagement between the metallic base and the non-metallic covering of both, an opening in the drain board about which 35 opening the non-metallic covering of the drain board is rabbeted, means for engaging the basin

to the drain board comprising a binding element having a recess to receive the metallic base of the drain board and the rabbeted edge of the non-metallic covering thereon, the non-metallic covering of both structural elements being applied to their respective bases to leave an interval between coverings extending along the junction line between the drain board and the splash board, adjacent edges of the coverings on both elements being rabbeted, and a binding strip of 10 relatively rigid material comprising legs disposed angularly to each other and engaged in the rabbeting of the covering on both the drain board and the splash board.

15. In sink construction comprising a splash 15 board and drain board set angularly to each other along their adjacent edges, and a basin depending below the plane of the drain board at an opening therein, the splash board and drain board being basically of sheet metal, complete 20 covering of non-metallic yielding material of substantial thickness on both the drain board and the splash board, said covering being rabbeted at its edge surrounding the basin opening in the drain board and at the adjacent edges 25 on the drain board and the splash board, and relatively heavy edging strips lying in the rabbeting at the edge of the basin opening in the drain board and engaging the adjacent rabbeted edges of the covering on the drain board and 30 the splash board, said metallic edging strips having their outer surfaces flush with the surfaces of the covering elements in the edge rabbeting of which they lie.

EUGENE E. BREY. 35
